OIL WELL DRILLING APPARATUS

August R. Maier, Dallas, Tex., assignor to Oil
Well Supply Company, a corporation of New
Jersey

Original application June 15, 1936, Serial No.
85,398. Divided and this application Septem-
ber 7, 1939, Serial No. 293,861

3 Claims. (Cl. 60—97)

This invention relates to improved control means for a plurality of engines arranged to be coupled together, and more particularly to a combined steam control and valve gear operating mechanism of the character hereinafter more fully shown, described and claimed.

The present invention is a division of the invention disclosed in my co-pending application Serial No. 85,398, now abandoned. For a more complete understanding of the present invention and the novel features which distinguish it from the teachings of the prior art, reference should be made to the following detailed disclosure, the accompanying drawings, and the appended claims.

In drilling wells, such as oil wells or gas wells, by means of a rotary drilling apparatus, a vertical drill stem carrying a bit on its lower end is rotated about its axis by means of a "rotary" having a horizontal rotating table through which the drill stem passes and which is squared to permit the latter to gradually be lowered during rotation. The drill stem is hollow and mud is pumped downwardly through this drill stem into the bottom of the well and flowing up about the drill stem carries with it the cuttings, which are separated, and the mud returned. The pumping of the mud and the rotation of the rotary and drill stem occur simultaneously and continue until the top of the squared part of the drill stem reaches or approaches the rotating table of the rotary. At this point the rotation of the drill stem and the pumping of mud through it are stopped and the drill stem is hoisted from the well so that an additional joint of the hollow stem may be joined below the squared element which is called a "Kelly," whereupon the drill stem is again lowered until the squared part or "Kelly" engages the rotary table. Thereupon the rotation of the drill stem and the pumping of mud are resumed and the stem gradually lowered as the drilling proceeds. This sequence of operation continues until the well reaches the desired level or until oil is found or the hopes of finding it are abandoned. As the drilling proceeds also the well is lined with casing to prevent cave-in, etc.

The hoisting of the drill stem requires a large amount of power, as the weight of the drill stem and associated tools, or of the casing pipe when the well becomes very deep, is very great; sometimes as much as 300 tons. The power required to drive the rotary is relatively very small, as is also the power required to drive the mud circulating pump. Heretofore the same engine has generally been used for driving the rotary and

driving the hoist. However, the conditions required to supply the power required for the hoisting mechanism are not such as to favor the efficiency of the engine through the relatively longer periods when it is driving the rotary, and the efficiency of the engine is, therefore, very much smaller during the rotary-driving periods than could be obtained if an engine were used at this period suited to the power requirements of the rotary. The power requirements for the mud pumps are also quite different from those of the rotary and hoist, and the best results are obtained when the pumps are driven by individual engines.

15 In my present invention, an arrangement of individual engines for the rotary and pumps and of a size to give an efficient use of steam during the rotary drilling operations, is provided and arranged so that they may be combined to drive the hoist during the hoisting operation, and to provide sufficient power for this latter purpose.

The engine driving the rotary must be reversible so that the rotary table may be turned in either direction, and both engines when combined for hoisting must be simultaneously reversible so that the hoist clutches, which are ordinarily of the jaw type, may be disengaged.

In the usual arrangement of drilling rigs and apparatus, the rotary is situated at the center of 30 the derrick floor and a draw-works including a hoisting drum is arranged at one side of the derrick floor. The driving engines are outside of the derrick, generally arranged between the mud pumps, draw-works and hoisting drums. This arrangement may also be used in my invention and the engine for driving the rotary may be connected to the jack shaft of the draw works and thence to the rotary, the hoisting drum being disconnected or unclutched from the jack shaft

40 while driving the rotary. The engine for driving the pump is aligned, or has its driving shaft aligned, with that of the rotary driving engine, and is provided with a clutch whereby this driving shaft may be clutched to the shaft of the rotary driving engine, so that the power from these

45 two engines may be combined and transmitted to the jack shaft of the draw-works. The rotary being disconnected or unclutched from the jack shaft, and the hoisting drum clutched to be driven from the jack shaft, the combined power of the two engines may be applied for driving the hoist. During this period the pump driving engine will be disconnected or unclutched from the mud pump.

An embodiment of the invention is illustrated

by way of example in the accompanying drawings, in which:

Figure 1 is a diagrammatic plan view of a rotary, draw-works, engines and pump, embodying a preferred form of the invention;

Figure 2 is a plan view of the rotary and mud pump driving engines;

Figure 3 is an elevation of the rotary and mud pump driving engines;

Figure 4 is an end view taken from the right of Figure 2;

Figure 5 is a plan view of a control mechanism for the engines, and

Figure 6 is a somewhat diagrammatic perspective view illustrating the unitary control mechanism which is effective to control the admission of steam to both engines and also the respective points of cut-off and reversal thereof.

In the embodiment of the invention shown in the accompanying drawings, an engine 10 for driving a mud pump 11, and an engine 12 for driving a rotary, both of these engines being reversing engines, are mounted on a common foundation, as, for example, on a pair of skids 13. The engine 10 is provided with a drive shaft 14 which projects from each end of the engine. A clutch element 15 connected to a sprocket 16 is rotatably mounted on the outer projecting end of the shaft opposite a complementary clutch element 17, slidably keyed on the projecting end of the shaft 14. When the clutch element 15 and sprocket are clutched to the shaft 14, the engine drives the pump 11 through the sprocket 16, the chain 18 and a sprocket 19 on the pump. The engine 12 is also provided with a driving shaft 20 which is coupled by means of a coupling 21 to a connecting shaft 22, aligned with the shafts 14 and 20, and carried between the pair of bearings 23 and 24 on the skids 13. A clutch element 25 is mounted on the end of the shaft 22 nearest the engine 10 and is slidable to engage and clutch with a clutch element 26 on the adjacent end of the drive shaft 14. Through the above mechanism it will be apparent that the shaft 14 may clutch at one end to drive the mud pump 11 and at the opposite end may be clutched to the connecting shaft 22. A control lever 27 is provided to throw the clutch 25 to clutching or de-clutching position. Another clutch lever 27' is connected by means of a link 28 to a clutch lever 29 engaging the clutch element 17. Consequently the engine 10 may drive either the pump 11 or the connecting shaft 22.

The rotary driving engine 12 is permanently connected or coupled to the shaft 22. The shaft 22 drives the jack shaft 31 of a draw-works 30. For this purpose it may be connected to the draw-works by any suitable means, as, for example, by a sprocket chain. Any suitable type of draw-works may be employed, a two-shaft draw-works being shown in the accompanying drawings by way of example. In this type, the draw-works may be driven alternatively by either one of a pair of driving chains 31 and 32 which are trained about respective sprocket wheels 33 and 34 and keyed on the shaft 22. The chains serve to drive sprocket wheels 35 and 36 respectively on the jack shaft 37 of the draw-works 30, to which the sprocket wheels may be alternatively clutched by clutches 38 and 39 to drive the jack shaft at either of two selected speeds. A sprocket wheel 40 rotatably mounted at one end of the shaft 37 may be clutched to the latter by a clutch 41 so as to drive a chain 42 which drives a rotary 43. It will be apparent that the chains 31 and 75

32 are continuously driven by the shaft 22 and may be alternatively clutched to the shaft 37, and that the shaft 37 may be clutched to the sprocket wheel 40 to drive the rotary 43 or may be unclutched therefrom. This shaft 37 may be clutched by means of a clutch 44 to a sprocket wheel 45 at the end of the shaft opposite the sprocket wheel 40 or may be clutched by a clutch 46 to a sprocket wheel 47 intermediate the sprocket wheel 35 and the sprocket wheel 40. The sprocket wheels 45 and 47 may drive a hoisting drum 48 alternatively through chains 49 and 50 respectively.

Through the above arrangement it will be apparent that when the clutch 26 is unclutched and the clutch 17 engages the clutch element 15, the engine 10 will be connected only to the mud pump 11. The engine 12 may drive the jack shaft 37 of the draw works 30 through either of the sprocket chains 31 and 32. When it alone drives the jack shaft 37 the clutch 41 may be engaged to drive the rotary 43. When the hoisting drum 48 is to be driven, the clutch 41 is de-clutched, as is also the clutch member 17. Clutch element 26 is clutched with the clutch element 25, whereupon both of the engines 10 and 12 combine to drive the jack shaft 37. This jack shaft 37 may be connected to the clutches 46 or 44 to drive the hoisting drum 48, with the combined power of both of the engines 10 and 12.

The engines 10 and 12 are of sufficient size to furnish ample power for the pump and the rotary respectively, with an early steam cut-off and therefore with a good steam efficiency. When these engines are used for hoisting after the well has reached a great depth and when there is a long line of drill stem or of casing to be supported and hoisted, the power required necessitates a longer supply of high pressure steam to the engine pistons, and therefore it is necessary to lengthen the cut-off to very nearly the end of the stroke of the engines.

When the two engines are combined for hoisting, suitable mechanisms are provided for simultaneously and uniformly controlling the cut-off and the reversing of both engines and for controlling the admission of steam to them from the driller's station which is near one end of the hoist drum. This mechanism consists in a shaft rotatable to control the steam supply and having a telescoping or sliding part which is connected through a link to a rocking lever for controlling the cut-off and the reversing of the rotary drilling engine 12. This rocking lever is connected through a shaft to the rock shaft on the pump engine 10 so that the two may be coupled together by means of a clutch and simultaneously operated by the driller to obtain identical cut-offs for and reversal of both engines.

A specific embodiment of this control mechanism is diagrammatically shown in the accompanying drawings. Figure 6 shows the essential elements of the control means detached from the other operating parts, in the interest of clearness. In this view a number of parts carried by the main engine shaft are omitted for the purpose of simplicity of illustration.

A single throttle valve 51 is adapted to control the admission of steam to both engines 10 and 12. This throttle valve has a spindle connected to a rotatably controlled shaft 52 which telescopes into a rotatable slidable member 53 carried in a bracket 54 on a strut secured to a leg 55 of the draw works or derrick 30. The outer end of the slidable member 53 is provided with

a hand wheel 56 which is so mounted that it can be rotated about its axis and moved longitudinally thereof. Member 53 may also be held in any predetermined position of longitudinal adjustment, by means of a latch 57 suitably mounted on bracket 54. Rotatably mounted on the inner end of the member 53 near its connection with the shaft 52 is a block 58 which prevents the longitudinal movement of the member 53. This block has an upwardly extending lug 58a to which is pivotally connected a link 59 which is in turn pivotally connected to a cut-off, control, and reversing lever 60 for the engine 12. The block 58 permits rotation of the slideable element 53 on which it is rotatably mounted without changing its position, but it is so held on said element 53 as to move longitudinally with the latter and thereby to swing the cut-off, control and reversing lever 60 to different positions or angles as member 53 is shifted to different axial or longitudinal positions. The lever 60 is secured to a rock shaft 61 of engine 12 which is aligned with a similar rock shaft 62 of engine 10. Shafts 61 and 62 are adapted to be connected with one another through an intermediate shaft 63 which is connected by a universal joint 64 with the shaft 62 and which is arranged to be coupled at will with a shaft 61 when the clutch elements 65 and 66 are engaged. When the engines operate individually, the clutch elements 65 and 66 will be uncoupled, but when the two engines are combined or coupled in tandem, the clutch elements 65 and 66 will be engaged. When so engaged, the movement of cut-off, control and reversing lever 60 will act through shaft 61 and connecting shaft 63 to simultaneously and equally shift the cut-off and reversing lever 67 mounted on the shaft 62 to thereby control the cut-off of engine 10 or the reversing thereof. Likewise lever 67, when rotated to an extreme position, is effective to either change the point of cut-off or to reverse engine 10 independently of the operation of engine 12 at such times as the clutch elements 65 and 66 are disengaged. The same is true of the lever 60 when the clutch elements are disengaged. When the two engines are combined or operating in tandem, it is important that the valve control mechanism thereof be properly synchronized. The reverse drive for engine 10 is held in quadrant notches by a set screw on a lever 67 in cooperative engagement with the notches as shown in Figure 6, while operating the pump. This locking means is disengaged when the engines are operated in tandem, as for hoisting purposes, so that the reversing mechanism for the combined engines 10 and 12 can be instantly controlled from the driller's position, as shown. Synchronization is obtained by the coordination of parts described, which act in concert with the respective reversing and cut-off mechanisms of the two engines. Each engine is equipped with the conventional form of slide valve 10v and 12v which controls the admission of steam from the steam chest of each engine to the cylinders thereof. The engine 10 is equipped with a pair of eccentrics 70 which are connected by means of eccentric straps shown with the curved arcuate link 72 which is slotted for sliding engagement with the block 74 suitably connected with the actuating rod 75 of the slide valve 10v. This valve mechanism, known in the art as the Stephenson link motion, is effective to vary the point of cut-off of the slide valve 10v, and also, when shifted to proper position, to reverse the direction of rotation of the engine. For shifting the

slotted link, the shaft 62 carries a downwardly extended arm 76 which is connected therewith by a member 78, as shown.

The engine 12 is equipped with similar eccentrics 78—78, which similarly actuate a slotted arcuate link 79 having a block 80 for transmitting motion to the slide valve 12v through a valve rod 81. The link 79 of the valve mechanism is connected by a member 79a to a lever 82 secured to the shaft 61. Thus the point of cut-off for engine 12 can also be varied or the engine can be reversed upon shifting of the shaft 61 through lever 60 to the proper angular position. From the foregoing, it will be apparent that when the clutch elements 65 and 66 are engaged, the respective valve mechanisms for the two engines coupled together by the clutch 26 may be operated in proper synchronism so that optimum operating conditions will be maintained. It is advantageous, when the two engines are operating in unison, to control the supply of steam from a single point. This is effected by the steam control arrangement best shown in Figure 6.

When the engine 10 is driving the pump 11, the steam supply coming from the steam main 83 is controlled by a valve 68 which is connected with a by-pass pipe 84 and also connected by a pipe 85 with a pipe 86 which in turn connects the steam chests of both engines. The valve 69 in the pipe 86 is only open when the engines are combined to operate at tandem. During such tandem operation the valve 68 will be closed. Thus the supply of steam to both engines from the main 83 will be controlled by the throttle valve 51. When the engine 10 is driving the mud pump 11, the steam supply is controlled through the valve 68. At such times the valve 69 will be closed, and therefore the throttle valve 51 will control only the engine 12.

By utilization of the unitary control mechanism shown and described, it will be apparent that the rotary and the mud pump may be independently driven by their individual engines under conditions most suitable for the efficient use of steam. When hoisting is to be done, these engines may be disconnected from the rotary and pump and coupled together, then used to drive the hoisting drum. During this latter operation their cut-offs may be interconnected so that the cut-offs of both engines may be controlled as a unit simultaneously with the control of the throttle valves, these controls all being operable from the controller's station near the drawworks. Through the above invention, therefore, the steam may be utilized most efficiently during the pumping and rotary driving operations and be capable of furnishing the maximum power required for the hoisting drum.

While I have described quite specifically the construction and arrangement of the parts herein shown, it is to be understood that various structural changes may be made and rearrangements of the parts may be resorted to without departure from the invention as defined in the appended claims.

I claim:

1. A power plant and control mechanism therefor comprising two steam engines each adapted to independently drive separate units, means for coupling said engines together for driving a third unit requiring greater power than either of said units, and a unitary control mechanism for both engines comprising a steam line connecting both engines, a shut-off valve therein, a steam supply main, respective pipes connecting said main with

said steam line on opposite sides of said valve, a throttle valve in one of said pipes and a shut-off valve in the other of said pipes, whereby one of the engines may be controlled by the throttle valve while the other engine is independently operated, and permitting control of both engines by said throttle when the engines are coupled together.

2. A power plant and control mechanism therefor comprising two steam engines each adapted to independently drive separate units, means for coupling said engines together for driving a third unit requiring greater power than either of said units, and a unitary control mechanism for both engines comprising a steam line connecting both engines, a shut-off valve therein, a steam supply main, respective pipes connecting said main with said steam line on opposite sides of said valve, a throttle valve in one of said pipes and a shut-off valve in the other of said pipes, whereby one of the engines may be controlled by the throttle valve while the other engine is independently operated, and permitting control of both engines by said throttle when said engines are coupled together, reversing mechanisms for each of the two engines, means operative to actuate the reversing mechanism for the engine separately controlled by the throttle valve, a common actuating means for both reversing mechanisms operable when the engines are coupled together, and means con-

nected therewith for operating said actuating means and the throttle valve to selectively control one or both of said engines.

3. The combination with two steam engines each equipped with a slide valve and each having actuating mechanisms therefor capable of reversing and varying the point of cut-off, clutching means to couple both slide valve actuating mechanisms for simultaneous operation, an actuating member common to both valve mechanisms when said clutching means are engaged, a steam supply main, a throttle valve connected therewith, a pipe connection between both engines communicating with the throttle valve, a shut-off valve in said pipe connection normally open when both engines are coupled together and closed when they operate independently, a by-pass pipe line from said supply main around said throttle valve and said shut-off valve, a control valve in said by-pass line normally closed when the engines are coupled together and adapted to control the operation of one of said engines when said shut-off valve is closed, and manual control means operatively associated with said throttle valve and said actuating member, whereby the admission of steam to the two engines, the cut-offs thereof, and the direction of rotation thereof, are controllable from a single operating station upon actuation of said manual control means.

AUGUST R. MAIER.
